DISPOSABLE RAZOR

John De Bacco, House Springs, Mo., and Gerald
De Bacco, Baton Rouge, La.

Application December 14, 1950, Serial No. 13,438

Term of patent 14 years

(Cl. D22—3)

To all whom it may concern:

Be it known that we, John De Bacco, a resident of the city of House Springs, county of Jefferson, State of Missouri, and Gerald De Bacco, a resident of the city of Baton Rouge, East Baton Rouge Parish, State of Louisiana, citizens of the United States, have invented a new, original, and ornamental Design for Disposable Razors, of which the following is a specification, reference being made to the accompanying drawing, forming a part thereof, in which:

We claim:

The ornamental design for a disposable razor, substantially as shown.

JOHN DE BACCO.
GERALD DE BACCO.
